(57) **CLAIM**

The ornamental design for a pad portion for a padding suspension system for a combat/tactical helmet, as shown and described.

DESCRIPTION

FIG. 1 is a front perspective view of a pad portion for a padding suspension system for a combat/tactical helmet according to the present invention, shown in a position of use;

FIG. 2 is a perspective view of a pad portion for a padding suspension system for a combat/tactical helmet shown separately for clarity of illustration;

FIG. 3 is a front view of the pad portion shown separately in FIG. 2;

FIG. 4 is a rear view thereof;

FIG. 5 is a left side view of the present invention. The right side view is a mirror image thereof; and,

FIG. 6 is a top view of the present invention. The bottom view is a mirror image thereof.

The broken lines in the drawings depicting a combat/tactical helmet shell and other pads represent environmental subject matter that forms no part of the claimed design.
